H. L. JOHNSON,
CARTON SEALING MACHINE,
APPLICATION FILED APR. 18, 1914

1,195,229.

Patented Aug. 22, 1916.

UNITED STATES PATENT OFFICE.

HARRY L. JOHNSON, OF BATTLE CREEK, MICHIGAN, ASSIGNOR TO JOHNSON AUTOMATIC SEALER COMPANY, LIMITED, OF BATTLE CREEK, MICHIGAN.

CARTON-SEALING MACHINE.

1,195,229.

Specification of Letters Patent. Patented Aug. 22, 1916.

Original application filed August 1, 1912, Serial No. 716,178. Divided and this application filed April 18, 1914. Serial No. 832,899.

To all whom it may concern:

Be it known that I, HARRY L. JOHNSON, a citizen of the United States, residing at the city of Battle Creek, county of Calhoun, 5 and State of Michigan, have invented certain new and useful Improvements in Carton-Sealing Machines, of which the following is a specification.

This invention relates to improvements in 10 carton sealing machines.

My improvements of this application relate particularly to the delivery mechanism or means for the cartons, and are especially designed by me for embodiment in carton 15 making, and sealing machines such as are illustrated and described in Letters Patent #1,096,918, issued to me May 19, 1914, of which this is a divisional application.

The main objects of this invention are: 20 First, to provide in a carton sealing machine, an improved delivery mechanism for the cartons adapted to effectively deliver the cartons from the sealing conveyer without injury thereto. Second, to provide in a 25 carton sealing machine, an improved delivery mechanism having these advantages, which is simple in structure and very durable and reliable in use.

Further objects, and objects relating to 30 structural details, will definitely appear from the detailed description to follow.

I accomplish the objects of my invention by the devices and means described in the following specification.

35 The invention is clearly defined and pointed out in the claims.

A structure which is a preferred embodiment of my invention is clearly illustrated in the accompanying drawing forming a 40 part of this specification, in which:

Figure I is a detail plan view of the rear portion of a carton sealing machine embodying the features of my invention. Fig. II is a detail vertical central longitudinal 45 section through the delivery mechanism of the structure shown in Fig. I. Fig. III is a detail longitudinal section on a line corresponding to line 3-3 of Fig. II. Fig. IV is a detail horizontal section on the line 50 corresponding to line 4-4 of Fig. II. Fig. V is an enlarged detail vertical section on

the line corresponding to broken line 5-5 of Fig. IV.

In the drawings similar reference characters refer to similar parts throughout the 5 several views, and the sectional views are taken looking in the direction of the little arrows at the ends of the section lines.

Referring to the drawing, the main frame 1 is of suitable design and structure to 60 properly support the operative parts. Disposed centrally and longitudinally of the frame is a conveyer comprising a chain 2 provided with flights 3 and forms 4. The flights 3 are adapted to receive filled cartons and the forms 4 are adapted to receive carton blanks from a suitable blank feeding mechanism. The rear end of the conveyer is supported by the sprocket 5 on the shaft 6. The flights and forms move between the 70 conveyer ways 7 provided for the top and bottom reaches of the conveyer chain.

The structure illustrated relates to the carton delivery mechanism of a combined carton making and sealing machine such as is illustrated and described in my patent referred to. Further details of the conveyer are not described herein as they form no part 75 of this present invention. The means for feeding the blanks to the forms 4 and the 80 filled cartons to the flights 3 are not illustrated as such means form no part of this invention. The carton forming and flap folding and sealing mechanisms are not described in detail herein as they form no 85 part of my present invention. My patent referred to illustrates and describes in detail a suitable carton forming and flap folding and sealing mechanism. Other mechanisms, however, than that of my said 90 patent might be utilized, as will be readily understood by those skilled in the art to which this invention relates.

At the rear end of the machine the cartons carried by the flights 3 are discharged 95 or delivered to the delivery conveyer 8. The mechanism for effecting this delivery comprises the discharge belts 9 arranged in opposed pairs at the rear end of the conveyer. The belts 9 are actuated to engage 100 the cartons carried by the flights 3 and allow the cartons carried by the forms 4 to

pass. The belts 9 are carried by pulleys 10 and 11, the pulleys 11 being mounted on the vertical shafts 12 carried by the swinging frames 13. The pulleys 10 are carried by the shafts 14 mounted in suitable bearings on the main frame. The swinging frames 13 are mounted upon these shafts 14. The shafts 14 are provided with beveled gears 15 meshing with the beveled gears 16 on the shaft 6 of the conveyer. The pulleys 10 are fixed to the shafts 14 to drive the belts. The frames 13 are swung to and from engaging position by the cams 17 acting on the rollers 18 on the arms 19, the arms 19 being fixed to the main frame. The cams 17 are mounted on vertical shafts 20 carried by the swinging frame 13. These shafts 20 are connected by the gears 21 and 22 to the shafts 14 so as to be driven thereby and properly timed with the conveyer. By this arrangement the frames are swung from their engaging positions to permit the cartons on the forms 4 to pass into their engaging positions to engage the cartons on the flights 3 and deliver the same to the delivery conveyer 18.

To insure positive gripping of the packages by the belts I provide belt supports comprising supporting bars 23 arranged between the pulleys and carried by the cross bars 24 mounted on the bars 25. The bars 25 are mounted on blocks 26 carried by the shafts 12, see Fig. V. The pulleys 11 are loosely mounted on this shaft 12 and the shafts are pivoted in the frames 13 to permit the swinging of the belt supports. The belt supports are actuated by cams 27 on gears 21 which engage rollers 28 on the belt supporting bars 25, so that as the gears 40 are revolved the belts are swung toward each other to engage the cartons carried by the conveyer flights 3, the belts being swung apart to permit the cartons carried by the frame to pass.

45 By this simple arrangement of the parts I provide a delivery mechanism which effectively delivers the cartons without injury thereto and allows, as stated, a part of the cartons to pass. The delivery mechanism, however, is well adapted for use on machines where it is desired to deliver all of the cartons. I have illustrated and described my improvements as embodied in the machine adapted for making and sealing the cartons and have not attempted to illustrate or describe the same as embodied in other machines, as I believe the disclosure made will enable those skilled in the art to which my invention relates to adapt or embody the same as may be desired.

Having thus described my invention, what I claim as new and desire to secure by Letters Patent is:

1. In a structure of the class described, the combination with the conveyer, a dis-

charge means comprising belts arranged in opposed pairs at the sides of the conveyer, vertical shafts arranged one at each side of the conveyer, swinging frames mounted on said vertical shafts, pulley shafts on said swinging frames, pulleys for said belts mounted on said vertical shafts and said shafts carried by said swinging frames, cam shafts carried by said swinging frames, gears connecting said cam shafts to said vertical shafts, cams on said cam shafts, members coacting with said cams to swing said frames as the cams are revolved, belt supports comprising belt engaging bars and supporting bars therefor mounted at their outer ends on said pulley shafts carried by said swinging frames, and cams on said gears on said cam shafts arranged to act on said belt supports, all coacting for the purpose specified.

2. In a structure of the class described, the combination with the conveyer, a discharge means comprising belts arranged in opposed pairs at the sides of the conveyer, vertical shafts arranged one at each side of the conveyer, swinging frames mounted on said vertical shafts, pulley shafts on said swinging frames, pulleys for said belts mounted on said vertical shafts and said shafts carried by said swinging frames, cam shafts carried by said swinging frames, gears connecting said cam shafts to said vertical shafts, cams on said cam shafts, and members coacting with said cams to swing said frames as the cams are revolved, all coacting for the purpose specified.

3. In a structure of the class described, the combination with the conveyer, a discharge means comprising opposed belts, driven shafts, swinging frames mounted on said driven shafts, pulley shafts on said swinging frames, pulleys for said belts mounted on said driven shafts and said shafts carried by said swinging frames, cams for said swinging frames geared to said driven shafts, belt supports comprising belt engaging members and supports therefor mounted at their outer ends on said pulley shafts carried by said swinging frames, and cams arranged to act on said belt supports, all coacting for the purpose specified.

4. In a structure of the class described, the combination with the conveyer, a discharge means comprising opposed belts, driven shafts, swinging frames mounted on said driven shafts, pulley shafts on said swinging frames, pulleys for said belts mounted on said driven shafts and said shafts carried by said swinging frames, and cams for said swinging frames geared to said driven shafts, all coacting for the purpose specified.

5. In a structure of the class described, the combination with the conveyer, discharging means comprising opposed belts,

- swinging supporting frames therefor whereby the belts are swung to and from engaging position, means for actuating said frames, opposed supports over which said belts travel, and means for swinging said supports toward each other to bring the belts into engaging position.
6. In a structure of the class described, the combination with the conveyer, discharging means comprising opposed belts, swinging supporting frames therefor whereby the belts are swung to and from engaging position, and means for actuating said frames.
- 10 7. In a structure of the class described, the combination with the conveyer, discharging means comprising opposed belts, opposed supports over which said belts

travel, and means for swinging said supports toward each other to bring the belts 20 into engaging position.

8. In a structure of the class described, the combination with the conveyer, a discharge means comprising opposed belts, swinging supporting frames therefor, whereby the belts are swung to and from engaging position, and means for actuating said frames.

In witness whereof, I have hereunto set my hand and seal in the presence of two 30 witnesses.

HARRY L. JOHNSON. [L.S.]
